Primary Examiner — Jonathan J Han*Assistant Examiner* — Christen Pilar Brown*(74) Attorney, Agent, or Firm* — Marshall A. Lerner;
Steven J. Kim; KLEINBERG & LERNER, LLP(57) **CLAIM**

The ornamental design for a shoe midsole periphery, as shown and described.

DESCRIPTION

FIG. 1 is a front perspective view of a shoe midsole periphery in accordance with my new design;

FIG. 2 is a rear perspective view of the shoe midsole periphery thereof;

FIG. 3 is a front elevation view of the shoe midsole periphery thereof;

FIG. 4 is a rear elevation view of the shoe midsole periphery thereof;

FIG. 5 is a left side elevation view of the shoe midsole periphery thereof;

FIG. 6 is a right side elevation view of the shoe midsole periphery thereof;

FIG. 7 is a top plan view of the shoe midsole periphery thereof; and,

FIG. 8 is a bottom plan view of the shoe midsole periphery thereof.

Broken lines shown in the drawing represent portions of the shoe and form no part of the claimed design.
